PHONOGRAPH TONE ARM

Maurice M. Palo, Conneaut, Ohio

Application July 21, 1954, Serial No. 31,527

Term of patent 7 years

(Cl. D26—14)

To all whom it may concern:

Be it known that I, Maurice M. Palo, a citizen of the United States, residing at Conneaut, in the county of Ashtabula and State of Ohio, have invented a new, original, and ornamental Design for Phonograph Tone Arm, of which the following is a specification, reference being made to the accompanying drawing, forming a part hereof.

In the drawing:

Figure 1 is a perspective view of a phonograph tone arm showing my new design;

Figure 2 is a top plan view of the tone arm of Figure 1; and

Figure 3 is a side elevation, partly in section, of the tone arm of Figure 1.

I claim:

The ornamental design for a phonograph tone arm, as shown.
